UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

RETAINING-BATTEN FOR INSULATION, THERMAL OR OTHERWISE.

1,137,793.

Specification of Letters Patent.

Patented May 4, 1915.

Application filed November 9, 1911. Serial No. 659,323.

To all whom it may concern:

Be it known that I, HARRY H. SCHROYER, a citizen of the United States, and a resident of the city of Chicago, in the county 5 of Cook and State of Illinois, have invented certain new and useful Improvements in Retaining-Battens for Insulation, Thermal or Otherwise; and I do hereby declare that the following is a full, clear, and exact description of the same, reference being had to the accompanying drawings, and to the numbers of reference marked thereon, which form a part of this specification.

This invention relates more particularly 15 to a metal batten adapted for use in insulating joints in structures, for example, the inner walls of cars or the like to protect the same from thermal changes at the joints.

It is also an object of the invention to afford a construction adapted to hold any insulating filling material such as mineral wool, or other suitable material, from displacement, and also to afford means for rigidly engaging or lining the retaining bolts 25 or screws in position to prevent the loosening of the insulating strip because of vibration.

The invention is hereinafter more fully illustrated and described in one of its preferred forms.

In the drawings: Figure 1 is a face view of a device embodying my invention, showing the same applied to cover a joint in a side wall or ceiling. Fig. 2 is a transverse 30 section illustrating the application of a batten embodying my invention, in insulating a corner joint. Fig. 3 is a transverse section illustrating the application and use of the invention. Fig. 4 is an enlarged fragmentary front elevation illustrating the construction whereby the retaining prongs both for the screw and for the filling material, are provided. Fig. 5 is a section taken on line 35 5—5 of Fig. 4.

As shown in the drawings: 1, indicates the covering wall or top boards, which may be either of wood, metal or any suitable material, the joints between which it is desired to insulate from thermal changes. The retaining batten, as shown, is constructed of 40 rolled or pressed metal to afford a top portion 2, and diverging side walls 3, affording

a channel having flaring flanges or walls, and adapted to receive the insulating material 4, which may be mineral wool, felt, or 45 any suitable material therein. The top or web of said batten, and the flanges thereof (or either or both of the same) may be constructed plain, as shown, or may be of any desired ornamental configuration, if preferred, dependent upon the character of use to which the same is to be put. The web of said batten is punched at intervals in its length to afford apertures for the attaching screws or bolts 6, and, as shown, the 50 web of the metal at each of said perforations, is slotted radially of the perforation somewhat beyond the same, and the triangular points afforded at each side of such slot, the one 7, turned outwardly to yieldingly 55 engage the head of the bolt to afford a lock therefor, and the other 8, turned inwardly to engage in the packing material, as shown in Fig. 3. Of course, any desired number of 60 said resilient retaining points may be provided.

In attaching the batten, the same is filled with the mineral wool or other insulating material, and the bolts or screws turned home, so that the head thereof engages the 65 out-turned points 7, pressing the same inwardly substantially flush with the face of the web to afford a smooth finish, each of said points engaging the under side of the head and yieldingly holding the same from 70 retraction or loosening because of vibration or otherwise. Of course, if desired, said battens may be used to cover or inclose and protect the walls of an electric circuit, in which event the mineral wool or other retaining 75 material may or may not be used, as preferred.

I have shown but one (and that a simple and preferred) embodiment of my invention. I therefore do not purpose limiting 80 the patent to be granted on this application otherwise than necessitated by the prior art.

I claim as my invention:

The combination with a surface to be covered, of a channel member fitting thereon, a filling within said channel member, and a series of screws passed through apertures in said channel member and into said surface

to be covered, the apertures receiving said screws being slotted radially and formed into barbs turned inwardly and outwardly therefrom to engage the screw head on the outside and to engage the filling material on the inside.

In testimony whereof I have hereunto

subscribed my name in the presence of two subscribing witnesses.

HARRY H. SCHROYER.
